GARMENT CONSTRUCTION

Mabs Ryden Barnes, Palos Verdes Estates, Calif., assignor to Hollywood Silk Mills, Los Angeles, Calif., a co-partnership composed of Mabs Ryden Barnes and Wallace E. Barnes

Application November 7, 1938, Serial No. 239,194

3 Claims. (Cl. 2—67)

This invention pertains to a garment particularly adapted for use in bathing and sports, the garment being essentially made of a woven, relatively non-yielding and non-stretchable material but provided with portions of resilient material or fabric, such as fabric containing lastex thread. The garment of this invention, although of unitary type, is arranged with convenient outlets which obviate the necessity of completely disrobing and is so constructed that persons differing in torso length are capable of being suitably fitted by the same garment.

Ordinarily, garments are made to fit a specified bust or waist measurement, the length of the garment being an arbitrary average. Persons having identical bust and waist measurements, however, will often vary as much as four or even six inches in torso length or distance between the shoulders and crotch. Usual garments, therefore, will not fit all persons of a specified bust or waist measurement and variations in torso length are particularly noticeable when the garment is of a type which must be provided with panties capable of fitting closely, as, for example, a bathing suit, play suit, etc. The improved construction to which this invention pertains permits a garment to be automatically adjusted to variations in torso length of the wearer.

Furthermore, the ordinary bathing and play suits require that the wearer completely disrobe in the event he wishes to enjoy the facilities of a bathroom or lavatory whereas the garments of this invention are so arranged and constructed that exposure of the upper portion of the body is obviated in such instances. Although the garments of this invention are provided with closely fitting pants made of a resiliently stretchable material including latex or rubber threads or the like, such pants are an integral part of the garment, and although the outer portion of the garment is made of a non-yielding or non-stretchable fabric, the mode of connection does not result in puckers nor is it obvious to an observer. Moreover, the construction of the garment assures retention of the bust within suitable pre-formed bust-receiving pockets even though the wearer is engaged in active sports.

An object of the present invention, therefore, is to provide a garment in which non-stretchable and stretchable fabrics are utilized to best advantage without detracting from a tailored appearance.

A further object is to provide a garment provided with convenient outlets which do not ne-

cessitate complete disrobing or exposure of the upper part of the body.

A still further object is to provide a garment including an outer portion and underlying panties, the panties forming an integral part of the garment but permitting relative movement of the garment with respect to said panties.

These and other objects of the invention will become apparent to those skilled in the art from the following detailed description which shall refer, for purposes of facilitating understanding, to the appended drawing, in which:

Fig. 1 is a three-quarter front view of one form of garment embraced by this invention.

Fig. 2 is a three-quarter rear view of the garment, in the position assumed by the garment when on the body, portions of the outer garment being broken away.

Fig. 3 is a vertical section taken through a breast-receiving pocket of the garment.

Generally stated, the garment comprises an outer portion made of any desired fabric or cloth, said outer portion being provided with preformed, substantially conical breast-receiving pockets and being adapted to cover the bust, torso and at least the upper portion of the thighs. Positioned within the garment are panties, preferably made of a resilient stretchable material, the upper front section of the pants being connected to the lower edge of the bust-receiving pockets by a connecting member of material capable of stretching freely in any direction, such material being generally referred to in the trade as "two way stretch."

In the type of garment shown in the drawing, the outer portion comprises bust-receiving pockets 10 and 11 and a skirt 12 connected to the bust-receiving pockets. Instead of the short skirt, the garment may terminate in a split skirt provided with large leg openings, or the lower portion of the garment may even continue downwardly so as to form long, wide pant legs. The garment is provided with shoulder straps 13 and 14 extending from the breast-receiving pockets 10 and 11 and over the back of the wearer. The back may be provided with a closure 15 which may be of any suitable type, preferably of the type known as the zipper; the bust-receiving portions 10 and 11 being made of a limp cloth or fabric and preferably connected at the sternum indicated by the seam 16, are preformed into substantially conical breast-receiving pockets terminating at the lower edges 17, the upper edge of each breast-receiving pocket being inclined upwardly toward each shoulder strap. The sides

of such breast-receiving pockets are connected by suitable underarm portions with the back or extend to the closure seam 15. Attention may be called to the fact, however, that the upper edge 5 of the back, indicated at 18, may be relatively low and may even lie below the bust-receiving portions 10 and 11.

As shown in Fig. 2, the garment also includes panties 20 made of resiliently stretchable material capable of firmly and closely fitting over the buttocks and hips and thereby suitably molding the figure. Such panties 20 are preferably provided with a readily releasable closure extending from a leg opening, such as the edge 21 of one leg 15 opening to the hip line or to the upper edge of the pantie, as indicated at 22. This closure 23 may also be of the Talon or zipper type. The lower edge 21 of the pantie 20 is preferably at a higher elevation on the body than the lower edge 20 of the skirt or outer portion 12, which is shown in Fig. 2 as simply a continuation of the breast-receiving pockets 10 and 11.

The front of the pantie 20 is connected to the lower edge 17 of the breast-receiving pockets by 25 means of a member 24 composed of a material resiliently stretchable both horizontally and vertically. The member 24 ordinarily extends over the entire front of the garment and is connected to the lower edges of the breast-receiving pockets 30 10 and 11 from one underarm portion to the other underarm portion, although the precise width of such connection may be varied. It is not necessary, however, for the connecting member to extend completely around the wearer and preferably such connection is only in the front of the garment, as stated.

In actual use it will be found that the bust is received in the breast-receiving pockets 10 and 11 and firmly retained therein, downward tension 40 through the resilient member 24 being exerted upon the lower edge 17 of such breast-receiving pockets, causing such seam or edge to lie against the body of the wearer immediately beneath the bust and effectively preventing the breast-receiving pockets 10 and 11 from crawling upwardly over the bust even though the wearer is engaged in active sports, swimming, or the like. Furthermore, since the member 24 is resiliently stretchable both horizontally and vertically, the outer 50 portion 12 of the garment may freely move over the pantie and over the connecting member 24 and the distance separating a bust-receiving pocket from the upper front edge of the pantie 20 may vary with bodily movements without destroying suitable supporting contact of such breast-receiving pocket with the body. The desirable feature of the releasable closure 23 need not be referred to again.

Since the upper edge of the back, indicated at 60 18, may be quite low (even below the level of the breast-receiving pockets 10 and 11), it is desirable that the run of material used in the back panels, such as the panel 26, be substantially in line with the shoulder strap 14 so that very little,

if any, bias exists along the edge 18 in the direction of the lower margin of the arm opening.

In view of the fact that the connecting member or section 24 is resiliently stretchable both horizontally and vertically, persons of different 5 torso length may wear the same garment provided, however, no great variation in bust measurement exists, the member 24 compensating for variations in torso length.

I claim:

1. A garment adapted for use in bathing and sports, comprising: an outer portion adapted to cover the bust, torso and upper thighs, said outer portion being made of relatively non-stretchable fabric and being provided with preformed breast-receiving pockets; a pantie made of elastic resilient material and adapted to closely fit the body, said pantie including a pair of leg openings and a substantially vertically extending closure from one of said leg openings; and a section of 20 resilient stretchable material connecting the lower inside edge of said preformed breast-receiving pockets with the top of the front portion of said pantie, said section being resiliently stretchable both horizontally and vertically, 25 whereby said pantie is integrally but yieldably associated with said outer portion.

2. A garment adapted for use in bathing and sports, comprising: an outer portion adapted to cover the bust, torso and upper thighs, said outer 30 portion being made of relatively non-stretchable fabric and being provided with preformed breast-receiving pockets; a pantie made of elastic resilient material and adapted to closely fit 35 the body, said pantie including a pair of leg openings and a substantially vertically extending closure from one of said leg openings; and a section of resilient stretchable material connecting the lower inside edge of said preformed breast-receiving pockets with the top of the front portion of 40 said pantie, said section being resiliently stretchable both horizontally and vertically, whereby said pantie is integrally but yieldably associated with said outer portion, downward tension in said section, when the garment is worn, tending to 45 maintain the bust of the wearer within said pockets.

3. A garment adapted for use in bathing and sports, comprising: an outer portion adapted to cover the bust, torso and upper thighs, said outer 50 portion being made of relatively non-stretchable fabric and being provided with preformed breast-receiving pockets; a pantie made of elastic resilient material and adapted to closely fit the body, said pantie including a pair of leg openings; 55 and a section of resilient stretchable material connecting the lower inside edge of said preformed breast-receiving pockets with the top of the front portion of said pantie, said section being resiliently stretchable both horizontally and vertically, whereby said pantie is integrally but yieldably associated with said outer portion.

MABS RYDEN BARNES.
